UNITED STATES PATENT OFFICE.

AUGUSTUS R. YOUNG, OF STILLWATER, MINNESOTA.

CAPSTAN.

SPECIFICATION forming part of Letters Patent No. 325,143, dated August 25, 1885.

Application filed March 25, 1885. (No model.)

To all whom it may concern:

Be it known that I, AUGUSTUS R. YOUNG, of Stillwater, in the county of Washington, and in the State of Minnesota, have invented 5 certain new and useful Improvements in Capstans; and I do hereby declare that the following is a full, clear, and exact description thereof, reference being had to the accompanying drawings, in which—
10 Figure 1 is a perspective view of my improved mechanism arranged for operation. Fig. 2 is a plan view of the upper side of the same, the covers for the pawl-heads being removed to show the arrangement of parts within said heads. Fig. 3 is a like view of said mechanism from the lower side. Fig. 4 is a vertical section upon lines xx of Figs. 2 and 3. Fig. 5 is a perspective view of the inner faces of the toothed upper end of the barrel and 15 the main pawl-head separated from each other. Fig. 6 is a like view of the minor pawl-head and its loose pinion separated from each other and from their carrying-shaft.

Letters of like name and kind refer to like 20 parts in each of the figures.

My invention relates to capstans in which, by a reversal of the motion of the driving-shaft, the winding-barrel is caused to rotate in the same direction with different velocities; 25 and my invention consists, principally, in a capstan in which are combined, with the winding-drum, two shafts that are adapted to be simultaneously rotated in either direction, and, by means of clutch mechanism and gearing, substantially as described, to alternately engage with and rotate said drum with different velocities, but always in the same direction, as the direction of revolution of said shafts is reversed, substantially as and for the 30 purpose hereinafter specified.

It consists, further, in a capstan in which are combined, with the winding-drum, an axially-journalized shaft that, when rotated in a forward direction, is adapted to engage with 45 and revolve said drum forward; a second shaft which journals a loose pinion that meshes with peripheral teeth upon said drum, and is engaged by and moved with said shaft when the same is rotated in a backward direction, 50 and means, substantially as shown, whereby

said shafts may be simultaneously rotated forward or backward, substantially as and for the purpose hereinafter set forth.

It consists, further, in a capstan in which are combined the following elements, to wit: 55 a winding-drum that is provided with peripheral gear-teeth, a shaft which is journaled axially within said drum, and by means of clutch mechanism is adapted to engage with and rotate the same when revolved in a forward direction; a second shaft that carries a loosely-journalized pinion, which meshes with the peripheral teeth of said drum, and by means of clutch mechanism is engaged by and revolves with said shaft when the same is 60 rotated in a backward direction, and means, substantially as shown, whereby said shafts may be simultaneously rotated in a forward or backward direction, substantially as and for the purpose hereinafter specified. 70

It consists, further, in the means employed for connecting the winding-barrel and loose pinion to or with their shafts, substantially as and for the purpose hereinafter shown.

It consists, further, in the means employed 75 for locking the clutch-pawls out of position for engagement, substantially as and for the purpose hereinafter set forth.

It consists, finally, in the construction and combination of parts, substantially as and for 80 the purpose hereinafter shown and described.

In the annexed drawings, A represents a shaft, which is journaled vertically within a suitable frame, B, and upon its lower end has attached a gear-wheel, C, that meshes with and 85 receives motion from a toothed wheel, D, upon a driving-shaft, E.

Upon the shaft A, above the frame B, is journaled a winding-drum, F, of usual form, upon the lower end of which is secured a gear-wheel, 90 G, that has preferably a diameter considerably greater than the diameter of such portion of said drum. Upon or within the upper end of said drum are provided a number of ratchet-teeth, f, which are arranged concentrically, and upon the projecting end of said shaft is secured a head, H, that extends radially over said drum at such point, and has pivoted within suitable recesses, h, two or more pawls, h', which are adapted to engage with 95 100

said teeth *f* when said shaft is revolved in a forward direction, and to trip and pass over the same when said shaft is turned backward.

Journalized within the frame B, at one side of the winding-drum F, is a shaft, I, which extends a short distance above said frame, and has loosely journalized upon its projecting portion a pinion, K, that meshes with the gear-wheel G at the lower end of said drum. Upon the upper end of said shaft is secured a head, L, which is similar in construction to the head H, and is provided with two or more pawls, *l*, that are adapted to engage with concentrically-arranged ratchet-teeth *k*, which are formed upon the upper face of the pinion K, which pawls and teeth are so arranged that when said shaft is rotated in a rearward direction said pinion will be engaged and caused to move with the same, and will, through said gear-wheel G, cause said drum to revolve in a forward direction.

The shaft I is connected with the shaft A by means of a third shaft, M, which carries a gear-wheel, N, and pinion O, a pinion, P, upon said shaft A, that meshes with said gear-wheel, and a pinion, Q, which meshes with said pinion O, the arrangement being such that while said shafts A and I will simultaneously revolve in the same direction the latter will make but one revolution while the former is making several revolutions.

The operation of the mechanism is as follows, viz: When the driving-shaft E is rotated so as to drive the shaft A in a forward direction, the pawls *h'* will engage with the teeth *f* of the drum F, while the pawls *l* will trip over the teeth *k* of the pinion K, by which means said drum will be caused to revolve with said shaft A with a considerable velocity, and said pinion K will be rotated loosely upon its shaft by the gear-wheel G. By reversing the motion of said driving-shaft said pawls *h'* will trip over said teeth *f*, while said pawls *l* will engage with said teeth *k*, by which means said drum will be driven in the same direction as before through the shafts A, M, and I, (with their meshing pinions and gears,) and the pinion K and gear-wheel G, such motion being many times slower than when said drum is driven directly by said shaft A, and the power capable of being exerted by said drum correspondingly greater.

In order that the pawls *h'* and *l* may be raised from contact with their engaging ratchet-teeth and locked in such raised position, the casing of each head H or L is made separate from the body or spider of the same, and is capable of being partially rotated in either direction upon such spider. At a suitable point within each casing *h²* or *l²* a stud, *h³* or *l³*, respectively, projects radially inward beneath each pawl *h'* or *l*, and when such stud is at or near the pivotal end of said pawl it in no manner interferes with the action of the latter; but when by the partial rotation of its casing said stud is moved to the opposite free

end of said pawl it raises and sustains said end out of contact with the ratchet-teeth below, and thus prevents the engagement of the part to which said head is attached with the part having the ratchet-teeth.

The mechanism described is preferably operated by power, and in order to change the speed of the winding-drum it is only necessary that the motor should be reversed, movement in one direction giving to said drum a rapid rotation, while a movement of said motor in an opposite direction operates to give said drum a much slower rotation with a corresponding increase in power.

Having thus fully set forth the nature and merits of my invention, what I claim is—

1. A capstan in which are combined with the winding-drum two shafts that are adapted to be simultaneously rotated in either direction, and by means of clutch mechanism and gearing, substantially as described, to alternately engage with and rotate said drum with different velocities, but always in the same direction, as the direction of revolution of said shafts is reversed, substantially as and for the purpose specified.

2. A capstan in which are combined with the winding-drum an axially-journalized shaft that when rotated in a forward direction is adapted to engage with and revolve said drum forward, a second shaft which journals a loose pinion that meshes with peripheral teeth upon said drum, and is engaged by and moved with said shaft when the same is rotated in a backward direction, and means, substantially as shown, whereby said shafts may be simultaneously rotated forward or backward, substantially as and for the purpose set forth.

3. A capstan in which are combined the following elements, to wit: a winding-drum that is provided with peripheral gear-teeth, a shaft which is journalized axially within said drum, and by means of clutch mechanism is adapted to engage with and rotate the same when revolved in a forward direction, a second shaft that carries a loosely-journalized pinion, which meshes with the peripheral teeth of said drum, and by means of clutch mechanism is engaged by and revolves with said shaft when the same is rotated in a backward direction, and means, substantially as shown, whereby said shafts may be simultaneously rotated in a forward or backward direction, substantially as and for the purpose specified.

4. As a means for connecting the shaft I with the winding-drum F, the pinion K, loosely journalized upon said shaft and provided with the ratchet-teeth *k*, the head L, secured upon said shaft and having the pivoted pawls *l*, and the toothed wheel G, secured to said drum and meshing with said pinion, said parts being combined to operate substantially as and for the purpose set forth.

5. As a means for releasing the pawls *h'* from and locking the same out of engagement with the ratchet-teeth *f*, the casing *h²*, surround-

ing the head H and adapted to be partially rotated around the same, and the pins or studs h^3 , which project from said casing radially inward beneath said pawls, said parts being 5 combined substantially as and for the purpose shown and described.

6. The hereinbefore-described capstan, in which are combined the shafts A, E, I, and M, the gear-wheels C, D, G, and N, the pinions O and P, the drum F, having the ratchet-teeth f , the loose pinion K, provided with the

ratchet-teeth k , and the heads H and L, having, respectively, the pivoted pawls h' and l , substantially as and for the purpose specified.

In testimony that I claim the foregoing I 15 have hereunto set my hand this 16th day of March, 1885.

AUGUSTUS R. YOUNG.
